AIR CUSHION VEHICLE

Melville W. Beardsley, Severna Park, and Philip W. Jackson, Jr., Silver Spring, Md., assignors to National Research Associates, Inc., Laurel, Md., a corporation of Maryland

Filed Aug. 17, 1960, Ser. No. 61,792

Term of patent 14 years

(Cl. D71—1)

FIG. 1.

FIG. 4.

FIG. 2.

FIG. 3.

FIG. 1 is a top plan view of an air cushion vehicle showing our new design;

FIG. 2 is a side elevational view thereof;

FIG. 3 is a front elevational view thereof; and

FIG. 4 is an enlarged detail view of the grid covering the circular vents fragmentarily shown in FIGS. 1, 2 and 3.

The essential features of our design for an air cushion vehicle reside in the circular grid covered vents around the top surface thereof in association with the particular seating area, especially the configuration of the foot-receiving portion thereof.

What is claimed is:

The ornamental design for an air cushion vehicle, as shown and described.
